MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

METHOD OF MAKING SHOES.

1,195,966.

Specification of Letters Patent. Patented Aug. 29, 1916.

Application filed September 14, 1915. Serial No. 50,630.

To all whom it may concern:

Be it known that I, MATTHIAS BROCK, a citizen of the United States, residing at Boston, in the county of Suffolk and State 5 of Massachusetts, have invented certain Improvements in Methods of Making Shoes, of which the following description, in connection with the accompanying drawings, is a specification, like reference characters 10 on the drawings indicating like parts in the several figures.

This invention relates to the manufacture of shoes and it has for its object to provide improvements in methods of preparing shoe uppers for pulling-over and lasting operations by which such operations 15 will be facilitated and other advantageous results secured.

When a shoe upper is assembled on a last 20 the vamp does not fit the toe of the last but flares outwardly over the top face of the toe and, because it is inconvenient to engage the margin of the vamp by the grippers of a pulling-over or lasting machine, 25 time is lost by the machine operators in inserting the upper into the grippers, particularly the pulling-over grippers. It has been proposed to mold the toes of vamps preparatory to lasting as explained in 30 United States Letters Patent No. 1,110,323, granted on application of B. J. Hamilton, and while the treatment disclosed in that patent causes the interior portion of the upper to fit the top and side faces of the 35 toe of the last, it leaves the margin of the forepart of the vamp difficult to seize by the pulling-over machine grippers.

The present invention, in its broadest aspect, introduces a new procedure in the 40 manufacture of shoes by shaping the margin of the forepart of a vamp so that it will present an upstanding edge around the toe of the last in close proximity to the edge of the last when the upper is assembled on the 45 last.

In another aspect, the invention contemplates combining in an advantageous way 50 an operation of molding the interior portion of the forepart of a vamp to the contour of a forepart form with a shaping of the margin of the vamp into an upstanding edge.

In the illustrated manner of practising 55 the new method, the margin of the forepart of the vamp is confined by applying holding

pressure on a narrow line between a table and a thin lower edge of a clamping member, then a relative movement of the confined and the unconfined portions of the vamp is effected in a direction transverse 60 to the plane of the confined portion to stretch the unconfined portion and shape it to a forepart form and thereafter the confined marginal portion is drawn out of the confining means against frictional resistance by further relative movement transverse to the plane of the confined portion. In this way the margin is subjected to a "drawing out" action between the table and the thin edge of said clamping member and thereby is stretched widthwise, is turned progressively into a plane substantially parallel with the molded portions of the vamp that are to cover the side faces of the toe, and is contracted lengthwise in a way to 75 shorten its outer edge line around the toe, to produce a permanently upstanding edge.

Other aspects of the invention contemplate deflecting the materials of the interior portion of the toe of the vamp out of the 80 plane of the margin before the margin is clamped to provide fullness of vamp stock which is used advantageously in the toe molding operation; moving the confined marginal portion forwardly at the sides of 85 the toe to straighten the tip seam ends before shaping the margin into the upstanding edge; directing the relative toe molding movement of the confined and unconfined portions of the vamp so as to carry the unconfined portion in a direction of definite 90 forward inclination to the plane of the confined portion for stretching the vamp lengthwise to obtain the stock to extend over the end of the toe of the forepart form; applying 95 pressure, with or without heat, to the stretched portion of the vamp on the top face of the forepart form to set it in its molded shape; and subjecting the inner side of the middle portion of the vamp to 100 the action of moist heat while leaving the marginal portion of the vamp substantially unaffected by the moisture.

My novel method may be practised in any appropriate manner, although under commercial conditions the assistance of mechanical means for confining the margin of the vamp and for acting upon the unconfined portion will be utilized as far as possible, substantially as pointed out in application 110

Ser. No. 714,452, filed Aug. 10, 1912, of which the present application is a division. In the apparatus described in said application, illustrations of which are furnished herewith as one form of suitable means for carrying out the present method, the confining of the margin of the forepart of the vamp is effected by clamping the vamp on a continuous line extending from near the tip seam at one side around the toe to a point near the tip seam at the other side, and the molding is effected by a forepart form which is pressed against the unconfined interior portion of the forepart of the vamp and caused to stretch and shape that portion of the vamp and finally, the clamping force being preferably modified, to draw out the margin from the confining means and bend it into substantially parallelism with the side faces of the forepart form. These stretching and shaping forces may be applied with good results in the order recited, but it is to be understood that in its broadest aspects the invention is not limited to a treatment of the interior portion of the vamp.

In the accompanying drawings: Figure 1 shows by dotted and full lines respectively the shape of the forepart of a vamp before and after treatment in accordance with this invention. Fig. 2 is a side elevation of one form of apparatus by which the invention may be practised. Fig. 3 is a vertical section showing the margin of the forepart of the vamp clamped. Fig. 4 shows the interior portion of the forepart of the vamp being stretched and shaped to a forepart form by relative movement of the confined and unconfined portions. Fig. 5 shows the confined marginal portion being moved forwardly at the sides of the toe. Fig. 6 shows in more detail the arrangement for relieving the clamping pressure so that the margin can be drawn from within the confining means; and Fig. 7 shows the confined marginal portion of the forepart of the vamp drawn out widthwise and turned to present the upstanding edge around the toe shown in full lines in Fig. 1.

As a shoe upper is made, preparatory to assembling with an innersole on a last for the pulling-over and lasting operations, the forepart of the vamp is substantially flat so that if the upper were applied to the last in this condition the margin of the forepart of the vamp would flare outwardly away from the side faces of the toe portion of the last, as will be understood from the dotted lines in Fig. 1, and be difficult to insert in the pulling-over machine grippers. By the method of this invention the marginal portion of the forepart of a vamp is reshaped to the form shown in full lines in Fig. 1. The machine which I have found desirable for use in practising the method comprises

a work table 6 supported on a vertically sliding head 2 by a wedge 8 in a position inclined forwardly and downwardly toward the operator to facilitate the presentation of the work. The table is apertured to permit the movement of a forepart form 10 vertically through it. The form is supported at an inclination similar to that of the table and is moved by means of a plunger 12 which extends through guides 13, 14 in the sliding head 2, the lower end of the plunger being connected by a link 15 to the short arm of a bell-crank lever 16 operated by a treadle 18, all as shown in Fig. 2. A spring 20 is confined on the plunger between the guide 13 and a collar 21. Above the work table 6 is arranged a clamping member 25 shaped to engage the forepart of the vamp from a point adjacent to the tip seam on one side around the toe to a similar point on the other side of the forepart. When the plunger is raised by the treadle 18 it raises the form 10 and it acts through the spring 20 to raise the sliding head 2 and the table 6 from the position shown in Fig. 2 until the movement of the head and the table is interrupted by the clamping member 25 after which the spring 20 is compressed while the plunger and the form 10 continue to rise. The movement of the table 6 up to member 25 clamps the margin of a vamp outspread over the form and table and continued movement of the treadle raises the form and shapes the unconfined portion of the vamp to the contour of the forepart form. The wedge 8 is then retracted, to relieve the margin clamping force, by a lost motion connection 60, 62, 64 with the treadle-operated bell crank 16. In the illustration the confined marginal portion of the vamp is drawn out during the movement of the form 10 from the position shown in Fig. 4 to the position shown in Fig. 7, and as this occurs the margin is stretched widthwise and turned into approximate parallelism with the side faces of the forepart form. This drawing out operation also effects a shortening of the outer edge line of the forepart of the vamp, thereby contracting the margin lengthwise around the toe so that it will constitute an upstanding edge 80, Fig. 7, which, when the upper is assembled upon a last, will occupy a suitable position, in close proximity to the edge of the last, to be conveniently seized by pulling over or lasting machine grippers.

I prefer to subject the interior portion of the vamp to compression against the top face of the forepart form to assist in setting this portion of the vamp in its stretched and molded shape. In the machine shown in the drawings, this is secured by the use of a compression member 40 having a lower vamp-engaging face of

the same contour as the top face of the form 10. The member 40 is mounted on a sleeve stem 42 that can slide up and down in an adjustable bearing 43 in the head of the machine, and it has a pawl 44 for engaging the teeth of the pivoted ratchet lever 45 which is held toward the pawl by spring 46. The pawl and the ratchet hold the member 40 normally in an upraised position to facilitate the insertion and arrangement of the vamp on the work table. The pressure member is released from the ratchet 45 by the operator at the proper time and is pressed against the work by gravity and by a spring 48.

I prefer to subject the inner side of the middle portion of the forepart of the vamp to the action of moist heat while leaving the marginal portion substantially unaffected or affected to a less extent, by the moisture. This is accomplished in the illustrated apparatus by providing the forepart form 10 with a steam chamber which communicates with the vamp engaging surface of the form 25 by perforations and grooves through which steam or heated vapor is injected between the vamp and the form to soften that portion of the vamp which is to be bent over the top face of the form in shaping it. Steam 30 is supplied through a valve 30 and piping 26, 52, 50, passing also through the pressure member 40 to supply dry heat for use on the outer face of the vamp. The valve can be opened by the pressure of the workman's hands on the form 10, which depresses the valve, Fig. 3, against the resistance of springs 32. The valve can also be opened by the resistance encountered when the former is raised against the work, and the valve remains open and delivers heated vapor to soften the vamp while the vamp is being shaped. The work table 6 and associated parts become heated from the steam, but the margin of the vamp is protected from moisture by being clamped between the heated table and the member 25. The described heating arrangement supplies moist heat to the inside or lining face of the vamp and supplies dry heat to the outside or finished surface of the vamp.

Under some conditions I prefer to move the confined marginal portion of the vamp forwardly at the sides of the toe before drawing out and bending said margin into the upstanding edge 80 in order to give the end portions of the tip seam a desired location when the vamp is assembled upon its last. In the illustrated construction I accomplish this operation by providing the wedge 8 with upstanding teeth 66 which project through an elongated slot in the work table 6 into position to engage the vamp under the clamping member 25 and pull the clamped margin forwardly as the wedge is moved in the direction of the ar-

row, Fig. 6. The clamping member 25 may also be provided with coöperating teeth formed on the lower edge of a swinging plate 68 which is suspended from the member 25 by parallel links 70 acted upon by a spring 72 to maintain the plate 68 normally in the position shown in Fig. 6. When the wedge 8 is moved in the direction of the arrow, Figs. 5 and 6, preparatory to drawing out the flange, the teeth 66 and those on the plate 68 will force the flange forwardly at the sides of the toe. The links 70 lift the plate 68 to relieve excessive resistance against drawing out the portion of the vamp engaged by it.

In carrying out the method with the aid of the illustrative machine, the forepart of a vamp is spread out over the work table 6 when the parts are in the position shown in Fig. 2. The forepart form is preferably made to stand slightly above the plane of the table, as shown in Fig. 2, so that it deflects the interior portion of the vamp out of the plane of the margin, or "humps" it, to provide fullness for molding over the top and side faces of the forepart form without overstraining the vamp. The treadle is depressed to elevate the work table together with the form 10 to the position shown in Fig. 3 for clamping the marginal portion of the vamp against the member 25. The treadle is then further depressed and the form forced upwardly against the inner side of the portion of the vamp which is not confined between the table and the member 25. This stretches the interior portion of the vamp and shapes it to the contour of the forepart form as shown in Fig. 4. The stretching of the vamp results from a movement of the form in a direction of definite forward inclination to the plane of the confined marginal portion of the vamp. This presses the middle portion of the vamp slightly forward to furnish stock to shape over the top and end face of the forepart form. Steam is supplied to the form 10 for heating and moistening the inner side of the vamp. The workman can press down the form to open the valve and moisten the vamp immediately after putting it on the form. The workman releases the heated pressure member 40 for applying pressure and dry heat to the outer side of the clamp at such time as he chooses. The pressure member may be employed during the elevation of the forepart form 10 to restrain the vamp from pulling forwardly over the top face of the form 10. When the work has been allowed to set until it has acquired the shape of the form, the treadle will be further depressed to retract the wedge 8 and raise the form to the position shown in Fig. 7. The retraction of the wedge is accompanied by the forward movement of the margin of the vamp at the opposite sides of

the toe by means of the teeth shown in Figs. 5 and 6. The elevation of the form effects the drawing out of the margin of the vamp from between the clamping member 25 and the work table against the frictional resistance of those parts, and stretches the margin widthwise, contracting the margin lengthwise around the toe and turning and shaping it into the upstanding edge shown at 80 in Figs. 1 and 7. When the vamp with an innersole is assembled upon its last, this edge will stand approximately upright in close proximity to the edge of the last around the toe and in position where it can be conveniently engaged by the grippers of a pulling-over machine as well as subsequently by the gripper of a gripper lasting machine, by which machines the portions of the upper not shaped by the described operation will be stretched and folded over the innersole. The operation on the margin of the vamp also reduces its thickness so that the edge is in better shape for lasting smoothly.

Having explained the nature of this invention and described how it may be practised, I claim as new and desire to secure by Letters Patent of the United States:—

1. That improvement in methods of making shoes which includes, as preliminary steps preparatory to lasting, confining the margin of the forepart of the vamp, effecting relative movement of the confined and the unconfined portions of said forepart in a direction transverse to the plane of the confined portion to stretch the unconfined portion and shape it to a forepart form, allowing the vamp to set until it acquires the shape of the form, and then shaping the confined marginal portion into an upstanding edge by drawing it out of the confining means against frictional resistance; and subsequently assembling the shoe upper and an innersole upon a last and then stretching and shaping to the last those portions of the upper not shaped in the preliminary operation and folding the upstanding edge inwardly over the last bottom.

2. That improvement in methods of making shoes which consists in confining the margin of the forepart of the vamp and shaping the vamp locally over the high part of the toe by pressing it at that point away from the plane of the confined portion of the margin and continuing the pressure to force other parts of the unconfined portions away from said plane and shape them to other portions of the top face of a forepart form, and finally drawing out the confined portion to form an upstanding edge.

3. That improvement in methods of preparing shoe uppers for lasting which consists in molding the interior portion of the forepart of the vamp to the contour of a forepart form while holding the margin of

the vamp and then shaping the marginal portion of the forepart of the vamp into an edge standing in suitable relation to the molded portion to be conveniently inserted into the grippers of a pulling-over machine. 70

4. That improvement in methods of preparing shoe uppers for lasting which consists in molding the interior portion of the forepart of the vamp to the contour of a forepart form while holding the margin of the vamp and then stretching the marginal portion of the forepart of the vamp widthwise substantially throughout its width. 75

5. That improvement in methods of preparing shoe uppers for lasting which consists in molding the interior portion of the forepart of the vamp to the contour of a forepart form while holding the margin of the vamp and then shortening the outer edge line of the marginal portion of the forepart 80 around the toe to produce an upstanding edge.

6. That improvement in methods of preparing shoe uppers for lasting which consists in molding the interior portion of the forepart of the vamp to the contour of a forepart form while holding the margin of the vamp and then stretching the marginal portion of the forepart of the vamp widthwise and simultaneously contracting it 85 lengthwise around the toe to produce an upstanding edge. 90

7. That improvement in methods of preparing shoe uppers for lasting which includes confining the margin of the forepart 100 of the vamp, effecting a relative movement of the confined and the unconfined portions of said forepart in a direction transverse to the plane of the confined portion to stretch the unconfined portion and shape it to a 105 forepart form, and moving the confined marginal portion forwardly at the sides of the toe, and then shaping said marginal portion so that it will stand in suitable relation to the molded portion to be conveniently 110 inserted into the grippers of a pulling-over machine.

8. That improvement in methods of making shoes which includes, as preliminary steps preparatory to pulling-over and lasting, confining the margin of the forepart of the vamp, effecting a relative movement of the confined and the unconfined portions of said forepart in a direction transverse to the plane of the confined portion to stretch the 120 unconfined portion, and then stretching the margin of the forepart widthwise and contracting it lengthwise around the toe to cause it to occupy suitable position when assembled upon a last to be conveniently 125 seized by pulling-over or lasting machine grippers. 115

9. That improvement in methods of preparing shoe uppers for lasting which includes confining the margin of the forepart 130

of the vamp, effecting a relative movement of the confined and the unconfined portions of said forepart to press the unconfined portion in a direction of definite forward inclination to the plane of the confined portion to stretch and shape the unconfined portion to a forepart form, allowing the vamp to set until it acquires the shape of the forepart form, and then freeing the vamp 10 from the form; and subsequently assembling the upper and an innersole upon a last.

10. That improvement in methods of making shoes which includes, as a preliminary 15 step preparatory to pulling-over and lasting, confining the margin of the forepart of the vamp, shaping the unconfined portion to a forepart form, and then shaping the margin of the forepart of the vamp so that it will 20 present an upstanding edge around the toe of the last in close proximity to the edge of the last when the upper is assembled upon the last.

11. That improvement in methods of making shoes which includes arranging the margin of the forepart of a vamp between a thin lower edge of a clamping member and a table, applying holding pressure to said margin on a narrow line along said edge of 25 the clamping member, and shaping said margin into substantial parallelism with the sides of said forepart by forcing said forepart of the vamp upwardly from the table and into the clamping member for causing 30 the stock of said margin to be drawn out between said thin edge of the clamping member and the table.

12. That improvement in methods of making shoes which includes, as a preliminary 40 step preparatory to pulling-over and lasting, confining the margin of the forepart of the vamp and then drawing out the said margin widthwise from the confining means and turning it to present an upstanding edge extending around the toe of the vamp where it 45 will stand in close proximity to the last edge when the shoe upper is assembled for the pulling-over and lasting operations.

13. That improvement in methods of preparing shoes for lasting which consists in deflecting the materials of the interior portion of the toe of a vamp out of the plane of the margin to provide fullness, then clamping the margin of the toe of the vamp, and then 50 molding the interior portion of the toe to the approximate shape of the top and side faces of the toe portion of a last.

14. That improvement in methods of making shoes which includes, as preliminary 60 steps preparatory to lasting, confining the margin of the forepart of the vamp, effecting relative movement of the confined and the unconfined portions of said forepart in a direction transverse to the plane of the 65 confined portion to stretch the unconfined

portion and shape it to a forepart form, subjecting the stretched and shaped portions of the vamp on the top face of the forepart form to compression, and then freeing the vamp from the form; and subsequently assembling the shoe upper and an innersole upon a last and then stretching and shaping to the last those portions of the upper not shaped in the preliminary operation. 70

15. That improvement in methods of making 75 shoes which includes, as preliminary steps preparatory to lasting, subjecting the inner side of the middle portion of the forepart of a vamp to the action of moist heat, stretching the forepart of the vamp and 80 shaping it to a forepart form, subjecting the outer side of the vamp to the action of dry heat, and then freeing the vamp from the form; and subsequently assembling the shoe upper and an innersole upon a last and then 85 stretching and shaping to the last those portions of the upper not shaped in the preliminary operation.

16. That improvement in methods of making 90 shoes which includes, as a preliminary step preparatory to lasting, subjecting the inner side of the middle portion of the forepart of a vamp to the action of moist heat while leaving the marginal portion of the vamp substantially unaffected by the moisture; and subsequently stretching and shaping the upper to a last and folding the margin of the upper inwardly over the last bottom. 95

17. That improvement in methods of making 100 shoes which includes, as a preliminary step preparatory to lasting, subjecting the inner side of the middle portion of the forepart of a vamp to the action of heated vapor while the marginal portion of the forepart 105 is protected from the vapor.

18. That improvement in methods of making 110 shoes which includes, as preliminary steps preparatory to lasting, applying a vamp loosely over a forepart form and injecting heated vapor between the vamp and the form in such relation to the vamp as to soften the portion of the vamp which is to be bent over the top face of the form in shaping the vamp to the form. 115

19. That improvement in methods of making 120 shoes which comprises yieldingly clamping the margin of the forepart of a vamp from one side of the toe around the end of the toe and along its other side while leaving the vamp unclamped or less securely held across the body portion back of the toe, shaping the unconfined portion of the toe by pressing it away from the plane of the clamped portion and so stretching it widthwise of the toe and longitudinally, and simultaneously increasing the clamping pressure on the margin of the vamp proportionally to the stretching force applied to the unconfined portion of the vamp. 125 130

20. That improvement in methods of making shoes which consists in arranging the forepart of a vamp between a forepart form and a relatively yieldingly mounted clamping member on the one hand and an unyieldingly mounted clamping member on the other hand, and effecting successively a clamping of the margin of the vamp on a substantially continuous line from one side 5 around the toe to the other side and then a stretching and shaping of the unconfined portion of the forepart of the vamp by moving the forepart form and its associated clamping member relatively to the rigid 10 clamping member until the clamping of the margin of the vamp is effected, continuing the movement of the form relatively to the clamping member and increasing the clamping pressure until the stretching of the unconfined portion of the vamp is effected, and 15 20

then relieving the clamping pressure and allowing the margin of the vamp to be drawn out and shaped during further relative movement of the form and the clamping members.

25

21. That improvement in methods of preparing shoe uppers for lasting which consists in molding the interior portion of the forepart of the vamp to the contour of a forepart form while locating the portion 30 which is to be so molded by holding the marginal portion of the vamp, and then so shaping the marginal portion of the forepart of the vamp that it will stand in suitable relation to the molded portion to be conveniently inserted into the grippers of a pulling-over machine.

In testimony whereof I have signed my name to this specification.

MATTHIAS BROCK.

20. That improvement in methods of making shoes which consists in arranging the forepart of a vamp between a forepart form and a relatively yieldingly mounted clamping member on the one hand and an unyieldingly mounted clamping member on the other hand, and effecting successively a clamping of the margin of the vamp on a substantially continuous line from one side 5 around the toe to the other side and then a stretching and shaping of the unconfined portion of the forepart of the vamp by moving the forepart form and its associated clamping member relatively to the rigid 10 clamping member until the clamping of the margin of the vamp is effected, continuing the movement of the form relatively to the clamping member and increasing the clamping pressure until the stretching of the unconfined portion of the vamp is effected, and 15 20

then relieving the clamping pressure and allowing the margin of the vamp to be drawn out and shaped during further relative movement of the form and the clamping members.

25

21. That improvement in methods of preparing shoe uppers for lasting which consists in molding the interior portion of the forepart of the vamp to the contour of a forepart form while locating the portion 30 which is to be so molded by holding the marginal portion of the vamp, and then so shaping the marginal portion of the forepart of the vamp that it will stand in suitable relation to the molded portion to be conveniently inserted into the grippers of a pulling-over machine.

35

In testimony whereof I have signed my name to this specification.

MATTHIAS BROCK.

Correction in Letters Patent No. 1,195,966.

It is hereby certified that in Letters Patent No. 1,195,966, granted August 29, 1916, upon the application of Matthias Brock, of Boston, Massachusetts, for an improvement in "Methods of Making Shoes," an error appears in the printed specification requiring correction as follows: In the heading to the printed specification, strike out line 6 and insert the following: *Original application filed August 10, 1912, Serial No. 714,452. Divided and this application filed September 14, 1915, Serial No. 50,630;* and that the said Letters Patent should be read with this correction therein that the same may conform to the record of the case in the Patent Office.

Signed and sealed this 21st day of November, A. D., 1916.

[SEAL.]
